Primary Examiner — Marissa J Cash*Assistant Examiner* — Altaira J Swangin(74) *Attorney, Agent, or Firm* — Novick, Kim & Lee, PLLC; Jae Youn Kim; Hyun Woo Shin**CLAIM**

I claim, the ornamental design for a display device having transparent display buttons, as shown and described.

DESCRIPTION

FIG. 1 is a top, front, right perspective view of a display device having transparent display buttons showing my new design;

FIG. 2 is a top, rear, right perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines shown in the drawings show portions of the display device having transparent display buttons which form no part of the claimed design.
